PRESS BUTTON CONTROL FOR ELEVATORS
AND THE LIKETheodor Hoffmann, Berlin-Reinickendorf,
GermanyApplication February 23, 1933, Serial No. 658,027
In Germany February 25, 1932

6 Claims. (Cl. 187—29)

This invention relates to a press button control for elevators and the like, in which only one control circuit is employed, parallel to which different resistances are arranged which are individually actuated by means of press buttons. In this connection a bridge arrangement of resistances and a switching mechanism are employed which will be hereinafter described in detail. In this manner the arrangement is rendered insensitive to the voltage variations in the supply main as the operation of the resistance bridge arrangement is not influenced by voltage variations.

An embodiment of the invention is illustrated by way of example in the accompanying drawing in which:—

Fig. 1 is a diagrammatic view showing the entire principle of the resistance bridge.

Fig. 2 shows an elevator control in which this principle is utilized.

The arrangement and operation of the control will be hereinafter described.

If voltage is applied across a resistance 1—2, no current will flow through the wire 4—6 if the resistances 3—4 and 4—5 are equal (see Fig. 1). Resistance 1—6 is made equal to resistance 6—2. If for example the resistance 4—5 is varied, current will flow through the wire 4—6 until the resistance 3—4 becomes equal to the resistance 4—5. If a motor 41, relay or the like is connected up in the wire 4—6 and if a device 42, which for example changes the resistance branch 3—4, is actuated by the motor or relay, this device, if the resistance branch 4—5 has been intentionally changed by the device 43, will continue to operate until the resistance 3—4 is equal to the resistance 4—5 because at this instant no current flows through the wire 4—6 and a relay or motor connected up therein would become currentless. Thus by merely changing the resistance 4—5 it is possible to produce an arrangement which accurately follows these alterations and at the same time controls for example stopping places of an elevator.

In Fig. 2 a bridge resistance 1—8 is connected up to the supply main. 9—10 is a resistance in the cage 11 which is varied by press buttons 12 corresponding in number to the number of stopping places. A certain resistance corresponds to each press button and therefore to each stopping place. 13—14 is the other bridge branch. This bridge branch is similarly constructed to the resistance branch 9—10. The resistance in the resistance branch 13—14 is changed by one of a plurality of contact strips 15 separated from

one another each corresponding to a different floor and cooperating with a contact arm 16. The contact arm 16 is actuated for example by the motor 17 and thus alters the resistance 13—14. The motor 17 is connected to the points 18—19 5 of the bridge. These points correspond to the points 4—6 in Fig. 1. If by actuating a press button 12 a certain part of resistance 9—10 is switched in, the motor 17, if the same resistance is not switched in the resistance branch 13—14, 10 will run until the contact arm 16 and contact strip 15 have made the resistance 13—14 equal to the resistance 9—10. At this instant there exists no voltage between the points 18 and 19, so that the motor 17 stops. A further arm 20 15 cooperating with a plurality of contact strips 21 separated from one another and each corresponding to a different floor is rigidly connected to the contact arm 16. The individual stopping places are controlled by this second contact arrangement 20—21 which runs in synchronism with the contact arrangement 15—16. Wires, corresponding in number to the number of stopping places, extend from the contact bar 21 to the floor switches 22 which cooperate with a cam carrier 25 34 in the elevator shaft and are actuated from the cage or are actuated in accordance with the position of the elevator at the respective floors by apparatus in the engine room driven by the elevator winch 35. Two leads corresponding to the 30 upward and downward travel of the cage extend from the floor switches to the reversing relays 23 of the elevator motor 24.

The attraction of a relay 25 is retarded by the damper 26, the operation of which is illustrated 35 by way of example in the drawing, so that the contact 27 is only closed after a certain time has elapsed. 28 is an auxiliary relay which serves on the one hand for applying the voltage of the supply mains 30, 30a, 30b across the bridge resistance 1—8 by means of the contact 29, and on the other hand, for actuating the relay. The switching operation when controlling a certain stopping place takes place as follows.

Assuming that the cage 11 is at the fourth floor, 45 that is in its highest position so that the uppermost floor switch 34 is switched out by the cam carrier 34 which is fixed on the cage 11 by the connection 68 and for example a press button 12 in the cage is actuated which corresponds to 50 the second floor so that the resistance 33—10 in the cage 11 is switched in, the current will then flow along the following path:

The current flows from the supply mains phase 30b through the wire 46 to the relay 28, 55
